Inventor

A.R.Kay

By *O. Haughey, Jr.* Attorney

UNITED STATES PATENT OFFICE.

ANSEL R. KAY, OF DENVER, COLORADO.

WORDOMETER.

Application filed May 2, 1921. Serial No. 466,294.

To all whom it may concern:

Be it known that I, ANSEL R. KAY, a citizen of the United States, residing in the city and county of Denver and State of Colorado, have invented certain new and useful Improvements in a Wordometer; and I do hereby declare the following to be a full, clear, and exact description of the invention, such as will enable others skilled in the art to which it appertains to make and use the same.

The object of the invention is to provide a wordometer or word registering device for use in connection with typewriting machines as a means of keeping account of the number of words for the purpose of constituting the basis of charges for work, as by a public stenographer or for the information of employers as a means of determining the relative values or degrees of efficiency and industry of employees and the like; and furthermore to provide for this purpose a device which may readily be applied to a typewriting machine of any of the ordinary or commercial types either as a part of the machine or as an attachment thereto; and also to provide in this connection a device which will not interfere in any way with the usual operation of the typewriting machine, will not require any extra effort or movement upon the part of the operator in order that the word counting device may be actuated, which will not interfere with the use of the usual spacing bar or other devices when the counting mechanism is not required, and which may readily be disconnected when work not requiring a record is being done; and with these and related objects in view the invention consists in a construction, combination and relation of parts of which a preferred embodiment is shown in the accompanying drawing, wherein:

Figure 1 is a plan view of an apparatus embodying the invention applied in the operative position to the base of a typewriting machine, including the parts by which it is actuated.

Figure 2 is an elevation partly in longitudinal section of the same.

Figure 3 is a transverse section on the plane indicated by the line 3-3 of Figure 2.

Figure 4 is a detail view of the counter bar, detached.

Figure 5 is a similar view of the rock shaft.

The device consists essentially of a counter-bar 10 adapted to be arranged upon the space bar 11 of the typewriting machine or in the path of movement of the hand of an operator in approaching the space bar, so that without extra effort or resorting to any movement different from that required in the ordinary operation of a typewriting machine, the counter bar may be struck by the finger of the operator and depressed without however interfering with the independent operation of the space bar provided an operation of the machine is required which does not call for the use of the counter or measuring device; in connection with a counter 12 which is adapted to keep an accurate record of the number of operations of the counter bar.

Any suitable or preferred construction of counter, many of which are now on the market may be utilized, the type indicated having a plurality of disks arranged so that motion may be communicated from one to the other to provide for registering units, tens, hundreds, thousands, etc. Motion is communicated to the spindle 13 of the counter by means of a rock shaft 14 which when the device is to be applied as an attachment to a typewriting machine may be mounted upon a base 16 consisting of a bar held to the base of the machine by screws 17 or the equivalent thereof. This rock shaft is connected with a spindle of the counter by means of a coupling 18 provided with a counter lever 19 by which a relative adjustment of the counter-spindle with regard to the rock shaft may be effected, to the end that a full stroke movement of the counter bar will effect a full stroke registering movement of the counter.

The rock shaft is provided with a terminally free crank arm 20 at the end opposite to the counter, and the counter bar in the construction illustrated is in the form of a saddle adapted to straddle the space bar of the typewriting machine with a depending arm 21 provided at its lower end with an eye 22 for the reception of the extremity of said crank.

As illustrated, the counter bar being of the saddle form adapted to rest upon the space bar and being readily removable therefrom when the counter mechanism is not required, said counter bar is adapted to be supported by the space bar and to be elevated thereby after the counter bar has been

pressed by a stroke of the finger of the operator, but as above noted the space bar is adapted to be operated independently of the counter bar and without causing the movement thereof and hence without causing the operation of the counter, as when it is desired to space inward from the margin of a sheet for an indent or the like.

It will be understood that the principle of the operation of the device is that the space bar under ordinary circumstances is operated at the end of each word, and therefore the operations of the space bar may represent words. By placing the counter bar at or about the center of the length of the space bar, it is obvious that it is directly in the path of approach to the space bar by the fingers of the operator in the ordinary use of the typewriting machine, so that no additional effort or movement on the part of the operator is required in keeping an accurate account of the number of words written. In the event that spacing is desired without operating the counter, the space bar may be pressed at a point near one of the ends thereof.

Also in order that the counter attachment may readily be disconnected when not required or when a register of the words written is not necessary, the hanger depending from the counter bar is split or bifurcated to form a slot 24 into which projects a spring actuated retaining arm 25 preferably having a coil 26 attached to the base and adapted to be displaced or deflected to permit of the sliding of the terminal eye of the hanger out of engagement with the crank whereupon the counter bar may be lifted from the space bar. It may be as readily and quickly replaced by fitting the saddle over the space bar and sliding the eye of the hanger over the free end of the crank, engaging the spring or yielding retaining arm with the slot thereof.

Having thus described the invention, what I claim is:

1. A wordometer for typewriting machines having a counter mechanism, a counter bar consisting of a saddle adapted for arrangement in straddling relation with the space bar of the typewriting machine, and operating connections between said counter bar and the counter mechanism.

2. A wordometer for typewriting machines having a counter mechanism, a rock shaft operatively connected with the counter mechanism and provided with a crank, and a counter bar mounted above for movement in a path corresponding with the space bar of the typewriting machines and having a hanger engaged with the crank of said rock shaft.

3. A wordometer for typewriters comprising a counter mechanism, means for operating the counter mechanism, and a counter

bar for operating said means and adapted to occupy a position overlying the space bar of the typewriter without being connected thereto.

4. A wordometer for typewriting machines having a counter mechanism, a rock shaft operatively connected with the counter mechanism and having a terminally free crank, and a counter bar for operating relation with the space bar of the typewriting machine and provided with a hanger detachably engaged with said crank.

5. A wordometer for typewriting machines having a counter mechanism, a rock shaft operatively connected with the counter mechanism and having a terminally free crank, and a counter bar for operating relation with the space bar of the typewriting machine and provided with a hanger detachably engaged with said crank, said hanger being slotted and a yielding retaining arm being engaged with said slot.

6. A wordometer for typewriters comprising a base adapted to be positioned beneath the spacing bar of a typewriter, a counter mechanism secured to the base, a shaft for operating the counter mechanism journaled on the base, a counter bar for operating said shaft adapted to occupy a position overlying the space bar.

7. A wordometer for typewriters comprising a base adapted to be arranged in longitudinal alignment with the spacing bar of a typewriter, a counter mechanism secured to said base with the spindle extending longitudinally of the base, a shaft journaled on the base and extending longitudinally thereof and connected to said spindle, and a counter bar for operating the shaft and adapted to occupy a position overlying the spacing bar of a typewriter.

8. A wordometer for typewriters comprising a counter mechanism having its spindle arranged longitudinally with respect to the spacing bar of the typewriter, a counter bar overlying the spacing bar, and means connecting the counter bar to the spindle.

9. A wordometer for typewriters comprising a relatively narrow base adapted to be arranged beneath and in longitudinal alignment with the space bar of a typewriter, a counter mechanism arranged on said base and having its spindle arranged in longitudinal alignment with the space bar, a shaft journaled on said base below the space bar and operatively connected to said counter mechanism, and a counter bar connected to said shaft and overlying the space bar of the typewriter.

In testimony whereof I affix my signature in presence of two witnesses.

ANSEL R. KAY.
